UNITED STATES PATENT OFFICE.

MARCUS O. ANTHONY, OF CLEVELAND, OHIO, ASSIGNOR TO THE CINCINNATI TAG CO.,
OF CINCINNATI, OHIO, A CORPORATION OF OHIO.

PIN TICKET.

Application filed February 5, 1923. Serial No. 616,895.

To all whom it may concern:

Be it known that I, MARCUS O. ANTHONY, a citizen of the United States, residing at Cleveland, in the county of Cuyahoga and 5 State of Ohio, have invented a certain new and useful Improvement in Pin Tickets, of which the following is a full, clear, and exact description, reference being had to the accompanying drawings.

10 This invention relates to an improved pin tag or pin ticket that is used for marking articles of merchandise with such data as the price, size, lot number, etc., and which is of the same general nature as the marking pin tag shown in the patent to Bishop and Mapes, No. 858,330, issued June 25, 1907.

The primary purpose of the invention is to produce a pin tag or ticket having certain 20 marked advantages over the particular one above referred to as well as over all other previous types with which I am familiar.

More specific objects are to provide a comparatively simple, inexpensive and durable 25 marking pin tag or ticket which is so designed, constructed and of such nature as to facilitate its attachment to articles of merchandise; enhance its hold thereon; and prevent its catching on objects and thereby 30 being jerked loose, or sticking or otherwise injuring those handling the merchandise to which it is attached.

A still more specific object of the invention is to provide a device of the aforesaid 35 character wherein the pin, though its body portion and head may be permanently embedded within the ticket, functions much as a safety pin with the point positively embraced by the head, resulting in the attainment 40 of the objects above enumerated, with others hereinafter appearing.

In the accompanying drawing, Fig. 1 is a face view of a marking pin tag or ticket constructed in accordance with my invention; Fig. 2 is a perspective view showing the 45 reverse side of the ticket; Fig. 3 is an enlarged longitudinal section through the ticket; Fig. 4 is an enlarged perspective view, similar to Fig. 2, showing a part of 50 one of the layers of the ticket torn away to reveal the body portion and head of the pin; Figs. 5, 6 and 7 are edge views of the ticket illustrating the manner of attaching it to an article; and Fig. 8 is a face view of 55 the ticket attached to the article.

The device is composed of two main elements or constituents, a ticket A and a pin B. The ticket is formed of plies or layers a and a' of an appropriate material, such as paper, suitably secured together, as by 60 gluing, in the production of a card of proper thickness with the body portion b and head b' of the pin B embedded between the layers, the attaching portion b^2 of the pin projecting through the layer a' . The head b' extends 65 transversely and across the axis of the body portion and is connected thereto by an angular or diagonal part b^3 . The body portion b , part b^3 and the head b' are in a plane at right angles to the plane occupied by the 70 body portion b of the attaching portion b^2 .

The ticket A is provided at one end with a tab a^2 which contains the head b' and part b^3 of the pin, and the tab is adapted to be turned over on approximately the line defining the adjacent end of the body portion of the ticket. The attaching portion b^2 of the pin is of a length substantially equal to that of the body portion b . After the 75 layers a and a' have been secured together with the body portion and head of the pin embedded between them, the head b' and the adjacent portion of the tab a^2 are depressed, as indicated at a^3 , in line with the axis of the body portion b , producing in the head 80 b' a notch b^4 .

The ticket or tag may be attached to an article, in the manner illustrated in Figs. 5 to 7, by inserting the attaching portion b^2 of the pin through the article C and pressing 90 it upwardly against the underside of the article after which the tab a^2 may be brought down about the edge of the article and over the end of the pin to confine it within the depression a^3 , the notch b^4 positively embracing the point, as in the nature of a safety pin. It is obvious that the ticket need not 95 be applied to the edge of an article but may be applied to any part thereof by passing the attaching portion of the pin through 100 and back again so that the point occurs on the side of the material with the ticket, after which the tab may be bent about the point.

Attention is directed to the fact that the 105 head portion of the pin, extending transversely of the body portion and therefore being, in effect, a lateral corrugation, prevents the body portion from turning within the ticket and maintains the attaching por- 110

tion in a definite position with respect to the ticket. The presence of the head of the pin within the tab of the ticket has the effect of reinforcing the tab crosswise and 5 renders easier the bending of the tab over the point of the pin.

Having thus described my invention, what I claim is:

1. A device of the character set forth 10 comprising a ticket, and a pin having a body portion and head which are completely embedded within the ticket, the pin having also an attaching portion extending from one side of the ticket, the part of the ticket 15 containing the head of the pin being adapted to be turned over the point of the pin when the ticket is attached to an article of merchandise so that the embedded head of the pin positively engages over and confines said point.

2. A device of the character set forth 20 comprising a ticket, and a pin having a body portion and a head which are completely embedded within the ticket, the pin having also an attaching portion projecting 25 at an angle from one side of the ticket, the head of the pin being disposed transversely of the longitudinal axis of the body portion, the attaching portion of the pin being adapted 30 to be bent into proximity to the adjacent side of the ticket, and the part of the ticket containing the head being arranged to be bent over the free end of the attaching portion so that said head overlies said attaching 35 portion.

3. A device of the character set forth comprising a ticket made up of two plies of material, and a pin having a body portion and a head confined between said plies while an 40 attaching portion of the pin projects at an angle from the end of the body portion opposite the head through one of the plies, the head being disposed transversely of the axis of the body portion and said head and 45 the adjacent portion of the ticket being depressed in alignment with said body portion, the attaching portion of the pin being adapted to be bent into proximity to the adjacent side of the ticket while that part

of the ticket containing the head of the pin is adapted to be turned over the free end of the attaching portion with said end occupying the aforesaid depression.

4. A device of the character set forth comprising a ticket made up of two plies of material, and a pin having a body portion and a head confined between said plies while an attaching portion of the pin projects at an angle through one of the plies, the head being disposed transversely of the axis of the body portion of the pin and connected thereto by a diagonal part, the portion of the ticket containing the head and said diagonal part being in the form of a tab, the head and tab having a depression in axial alignment with the body portion, the attaching portion of the pin being adapted to be pressed into proximity to the adjacent side of the ticket while the tab is adapted to be turned over the free end of the attaching portion with the depression thereof occupied by said end.

5. A device of the character set forth comprising a ticket, and a pin having a portion that is corrugated transversely and embedded within the ticket and an attaching portion extending from one end of the embedded portion through one side of the ticket, the ticket being adapted to be attached to an article of merchandise through 80 the instrumentality of the attaching portion of the pin.

6. A device of the character set forth comprising a ticket, and a pin having a portion embedded within the ticket and an attaching portion extending from one side of the ticket, the portion embedded within the ticket being corrugated laterally thereby to prevent the pin from turning with respect to the ticket, the end portion of the pin opposite its attaching portion being adapted to be turned over the point of the attaching portion when said portion is pressed into proximity to the adjacent side of the ticket.

In testimony whereof, I hereunto affix my signature.

MARCUS O. ANTHONY.
